United States Patent Office

Des. 202,119
Patented Aug. 31, 1965

202,119

CUP

Richard K. Shelby, 1145 Hickory Trail,
Downers Grove, Ill.

Filed July 6, 1964, Ser. No. 80,705

Term of patent 14 years

(Cl. D44—9)

I claim:

The ornamental design for a cup, as shown.
